ABSTRACT

A portable hose stand system enables the user to project a stream of water from a water hose or hose nozzle in a fixed direction. A hose receiver is configured to receive and retain a hose and is coupled with pivot to allow adjustment of a desire water flow direction and a pivot retainer locks in a desired position. The hose receive is configured on an extended end of a hose extension that extends from a stand body. Retractable legs extend down from the stand body and pivot away from each other to provide a stable base. Water flow may be controlled through the use of a motion sensor valve. Lastly, a wall mount serves as a receiver for the portable hose stand system as a faucet and/or shower.

HOSE MOTION SENSOR VALVE SYSTEM**CROSS REFERENCE TO RELATED APPLICATIONS**

This application is a continuation in part of U.S. patent application Ser. No. 17/558,851, filed on Dec. 22, 2021, which claims the benefit of priority to U.S. provisional patent application No. 63/180,797, filed on Apr. 28, 2021; the entirety of all prior applications are hereby incorporated by reference herein.

BACKGROUND OF THE INVENTION**Field of the Invention**

The invention relates to a hose motion sensor valve system that enables the flow of water from a hose to be controlled by breaking a light curtain on a motion sensor valve.

Background

There are many situations when it would be desirable to have a fixed projection of a stream of water without holding the hose or nozzle. For example, when washing the car, a dog, equipment, or even for showering, the user may prefer using both their hands to do the task more efficiently. In addition, a person may want to project water over a specific area without having to be physically present such as watering the lawn or garden. Often times, an intermittent and controlled stream of water is desired and frequently turning the water off at a hose bib or by the nozzle can be time consuming and less water efficient. Some hose nozzles have levers or turn valves, but these may be difficult or cumbersome to function when hands are preoccupied or there is a preference to not transfer substances onto the respective “on” or “off” positions.

SUMMARY OF THE INVENTION

The invention is directed to a hose motion sensor valve system utilizing a motion sensor valve that is coupled with a hose, such as being configured proximal to the hose nozzle, such as between the hose receiver and the hose nozzle to provide a quick, efficient and convenient means to turn on and off the flow of water. A motion sensor valve enables the flow of water to be activated and stopped by motion, such as by placing your hand in a sensor curtain, such as a light curtain. A light curtain may include visible and/or non-visible light or electromagnetic radiation, including light from a light emitting diode. An exemplary motion sensor detects when a light curtain is broken. A sensor curtain is formed between a light emitter and light receiver and the motion sensor detects a break in the light. The light emitter may include a light emitting diode. The motion sensor is coupled with a valve actuator that opens and closes a valve to initiate and stop the flow of water through the motion sensor valve. The motion sensor valve may have batteries to power the system and a lock-out switch to disable the valve actuator to prevent unwanted stopping or starting of the flow of water. The lock-out switch may be switch to prevent the water from being turned on when the hose and portable hose stand are not in use, for example. The motion sensor valve may have an inlet to receive the hose and an outlet to couple with a hose nozzle for example. Each of the inlet and outlet may be threaded connections for coupling with the hose and

hose nozzle. The motion sensor valve may be used to conserve water. When washing a vehicle or a pet, it may be desirable to turn the water on and off as needed versus letting the water run continuously. The motion sensor valve may provide a quick and convenient means to only dispense water from the hose when needed.

A hose motion sensor valve system may be coupled with a portable hose stand system that includes a portable hose stand configured to retain a hose to direct a water spray in a specific direction. The stand may have retractable legs that enable a secure base for retaining the hose nozzle in an extended position from the stand body by a hose extension. The hose extension from the stand body may have a plurality of extension portions that are telescoping to enable the hose nozzle to be retained up above a person for showering, for example. A hose receiver may be configured on the extended end of the hose extension to enable the hose and/or hose nozzle to be detachably attached. A nozzle pivot may enable the hose nozzle to be directed in a desired direction and locked into place. The portable hose stand may be configured to be detachably attached to a wall mount, having one or more wall mount clips to retain the portable hose stand. The hose retainer may be coupled with the nozzle pivot and a nozzle pivot post may be configured to detachably attach to the extended end of the hose extension. This same nozzle pivot post may be configured to detachably attach to a wall mount adapter that is coupled with the wall mount.

An exemplary portable hose stand has retractable legs that pivot away from an extension leg and may also pivot away from each other to provide a stable base having three points of contact. The retractable legs may be coupled with a leg receptacle and a leg assembly pivot may enable the leg receptacle and retractable legs to pivot away from the extension leg. A leg assembly spring may force the leg receptacle and retractable legs to pivot away from the extension leg. Also, the leg assembly pivot may have a plurality of notches or apertures for receiving a pivot pin to secure the retractable legs in a pivoted orientation from the extension leg, such as at a retractable leg angle of about 30 degrees or more, about 45 degrees or more, about 60 degrees or more and any range between and including the retractable leg angles provided. In addition, the two retractable legs may be configured to pivot away from each other by a leg pivot spring, which may be a torsional spring configured around the leg pivot. The two retractable legs may pivot away from each other a leg angle of about 30 degrees or more, about 45 degrees or more, about 60 degrees or more, about 75 degrees or more and any range between and including the leg angles provided. Furthermore, the extension leg and/or the retractable legs may have a plurality of portions that telescope to enable adjustment of the length of the legs. This ability to change the length of the legs, in particular the retractable legs, enables the stand to be positioned for stability on uneven surfaces, such as on a sloped driveway or yard, for example.

An exemplary hose extension enables the hose receiver to be extended up away from the stand body. The hose extension may have a coupled hose extension that is coupled to the stand body and may extend from the extension leg. In an exemplary embodiment, the coupled hose extension extends into and out of the extension leg. The hose extension may have a first hose extension that extends from the coupled hose extension. A hose extension retainer may be configured to retain a hose extension in a desired extended position. A hose extension retainer may be a collar or clip that compresses the outer hose extension or extension leg around the inner hose extension. A hose extension assembly may have

one or more hose extensions, such as two or more, three or more, four or more or any range between and including the number of hose extensions provided. A plurality of hose extensions may be telescoping with one extending into the other. The hose extension may be configured to extend the hose nozzle to a height of about 1.5 m or more, about 1.75 m or more, about 2.0 m or more about 2.5 m or more and any range between and including the height values provided. These heights may be the height of the hose nozzle when the retractable leg angle is about 60 degrees, or wherein the extension leg and hose extensions extend at an angle of about 60 degrees from a horizontal ground surface.

A weight, such as a bucket and most preferably a collapsible bucket or weight bag may be retained to the portable hose stand to provide additional stability. A collapsible bucket may be made out of a fabric, a coated fabric, or film of material and may be configured to fold for storage. A collapsible bucket may have a flat base panel and a cylindrical side extending up from the base panel to retain water therein. When water is placed in the bucket the weight of the water may fill out the collapsible bucket so that it retains a bucket shape. The bucket may have a handle that is secured by the stand body, such as around one or more of the legs or to a hook configured on the stand body. The weight may be centrally configured under the stand body such as under and between the legs. The weight may hang from a hook on the stand body or the handle of the weight may extend around one or more of the legs. A collapsible bucket may have water placed therein, such as from the hose, to provide an effective weight for stability of the portable hose stand. When finished with the portable hose stand, the water in the collapsible bucket can be poured out and the collapsible bucket can be collapsed for compact storage.

A hose receiver may be configured on the extended end of the hose extension and may have a receiver clamp that can be squeezed to open a receiver channel for retaining the hose or hose nozzle. A hose receiver pivot may enable the clamp to open or move a first receiver portion with respect to a second receiver portion. A nozzle pivot 80 may be coupled with the hose receiver or with the hose nozzle to enable the hose nozzle to be directed in a desired orientation and locked into place by the nozzle pivot lock. A nozzle pivot post may extend from the nozzle pivot and be configured to extend into the extended end of the hose extension. The nozzle pivot post may have a nozzle pivot post retainer that is adapted to couple with a hose extension retainer. For example, the nozzle pivot post retainer may be a ball and the hose extension may have an aperture to receive the ball. Also, this nozzle pivot post may be configured to be inserted into and retained by a wall mount adapter that is coupled with a wall mount. In this way, the hose can be secured to a wall mount without the portable hose stand, or stand body and legs. The wall mount adapter may have an aperture to receive the ball or the nozzle pivot post retainer.

The portable hose stand may be configured to be retained by a wall mount having one or more wall mount clips. Two or more clips that are spaced apart may be preferred as it provides a more stable retention of the portable hose stand. The wall mount clips may be configured to clip around the extension hose, or one or more of the retractable legs. The wall mount may have apertures for attachment of the wall mount to a wall, such as by screws.

An exemplary portable hose stand system may be configured to enable a large number of applications, such as washing a car, dog, or equipment rinsing hands, feet, or body, and sprinkling or watering the lawn, and the like. Any number of hose nozzles may be coupled with the hose

receiver and/or the motion sensor valve outlet. The hose nozzle may be extended up high to enable an outdoor shower, or for rinsing a vehicle. The extension legs and hose extensions may help to enable directing water in a desired an outstretched direction, such as up and into gutters, for example. A sprinkler head may be attached to the portable hose stand to enable watering the lawn or garden. The portable hose stand may be used when in the wall mount as an outdoor shower as well.

Portable, as used herein, means that the hose stand can be picked up and carried manually from one location to another and, as described herein, has legs for supporting a hose in an elevated position.

The summary of the invention is provided as a general introduction to some of the embodiments of the invention, and is not intended to be limiting. Additional example embodiments including variations and alternative configurations of the invention are provided herein.

BRIEF DESCRIPTION OF SEVERAL VIEWS OF THE DRAWINGS

The accompanying drawings are included to provide a further understanding of the invention and are incorporated in and constitute a part of this specification, illustrate embodiments of the invention, and together with the description serve to explain the principles of the invention.

FIG. 1 shows a side view of the exemplary portable hose stand system with the retractable legs pivoted out from the extended leg and with the hose extension assembly extended to raise the hose nozzle up over the person's head for showering or for reaching higher target areas.

FIG. 2 shows a side view of the exemplary portable hose stand being held by a person to extend the spray from the hose nozzle up above the person.

FIG. 3 shows a side view of a sprinkle head nozzle retained by the hose receiver of the exemplary portable hose stand.

FIG. 4 shows a side view of a portion of the exemplary portable hose stand system having a motion sensor valve apparatus comprising a motion sensor that is coupled with a valve that opens and closes as a function of motion being detected.

FIG. 5 shows a perspective view of the exemplary portable hose stand secured on a ground surface by the extension leg, extending from the hose extension and two retractable legs that are pivoted away from the extension leg by a leg assembly pivot and away from each other by a leg pivot.

FIG. 6 shows a perspective view of a portion of the exemplary portable hose stand system secured on a ground surface and having a weight coupled to the stand to prevent the stand from tipping over during use.

FIG. 7 shows a left side view of the exemplary portable hose stand.

FIG. 8 shows a back view of the exemplary portable hose stand.

FIG. 9 shows a right side view of the exemplary portable hose stand.

FIG. 10 shows front view of the exemplary portable hose stand.

FIG. 11 shows a right side view of a portion of the exemplary portable hose stand with the leg receptacle pivoted into the extension leg.

FIG. 12 shows a right side view of a portion of the exemplary portable hose stand with the leg receptacle pivoted away from the extension leg.

FIG. 13 shows a back view of a portion of the exemplary portable hose stand with the retractable legs pivoted toward each other and retained by the stand body.

FIG. 14 shows a back view of a portion of the exemplary portable hose stand with the retractable legs pivoted away from each other by the leg pivot spring.

FIG. 15 shows a right side view of a motion sensor valve having a motion sensor valve having a motion sensor that is coupled with a valve actuator to open and close a valve for water supply to the hose nozzle, not shown.

FIG. 16 shows a bottom view of the motion sensor valve shown in FIG. 15.

FIG. 17 shows a back view of the motion sensor valve shown in FIG. 15.

FIG. 18 shows a left side view of the motion sensor valve shown in FIG. 15.

FIG. 19 shows a front view of the motion sensor valve shown in FIG. 15.

FIG. 20 shows a side view of the exemplary portable hose stand detachably attached to a wall mount.

FIG. 21 shows a top view of an exemplary wall mount.

FIG. 22 shows a back view of the exemplary wall mount shown in FIG. 21.

FIG. 23 shows a right side view of the exemplary wall mount shown in FIG. 21.

FIG. 24 shows a front view of the exemplary wall mount shown in FIG. 21.

FIG. 25 shows a top view of an exemplary hose receiver having a receiver clamp to open and close the hose receiver channel.

FIG. 26 shows a front view of the hose receiver shown in FIG. 25 coupled with a nozzle pivot having a nozzle pivot post.

FIG. 27 shows a front view of the hose receiver shown in FIG. 25 coupled with a nozzle pivot having a nozzle pivot post.

FIG. 28 shows the hose receiver shown in FIG. 25 coupled with a wall mount by the nozzle pivot post.

Corresponding reference characters indicate corresponding parts throughout the several views of the figures. The figures represent an illustration of some of the embodiments of the present invention and are not to be construed as limiting the scope of the invention in any manner. Some of the figures may not show all of the features and components of the invention for ease of illustration, but it is to be understood that where possible, features and components from one figure may be included in the other figures. Further, the figures are not necessarily to scale, some features may be exaggerated to show details of particular components. Therefore, specific structural and functional details disclosed herein are not to be interpreted as limiting, but merely as a representative basis for teaching one skilled in the art to variously employ the present invention.

DETAILED DESCRIPTION OF THE ILLUSTRATED EMBODIMENTS

As used herein, the terms "comprises," "comprising," "includes," "including," "has," "having," or any other variation thereof, are intended to cover a non-exclusive inclusion. For example, a process, method, article, or apparatus that comprises a list of elements is not necessarily limited to only those elements, but may include other elements not expressly listed or inherent to such process, method, article, or apparatus. Also, use of "a" or "an" are employed to describe elements and components described herein. This is done merely for convenience and to give a general sense of

the scope of the invention. This description should be read to include one or at least one and the singular also includes the plural unless it is obvious that it is meant otherwise.

Certain exemplary embodiments of the present invention are described herein and are illustrated in the accompanying figures. The embodiments described are only for purposes of illustrating the present invention and should not be interpreted as limiting the scope of the invention. retained in an extended position with respect to the coupled hose extension 51 by a hose extension retainer 58. The hose extension retainers may be collars or clamps that compress the two hose extensions together to prevent sliding. A hose receiver 70 is configured on the extended end 54 of the hose extension by a nozzle pivot 80 that enables the hose nozzle 18 to be pivoted about the hose extension or extension axis 13. A hose motion sensor valve 190 is configured between the hose receiver and the hose nozzle 18 and has a motion sensor to enable quick turning on and off of the spray of water from the hose nozzle.

As shown in FIG. 2, the exemplary portable hose stand system 10 is being held by a person 120 to extend the water spray 11 from the hose nozzle 18 up above the person. Note that the hose extension assembly 50 is not fully extended with the first hose extension 56 only partially pulled out from the coupled hose extension 51.

As shown in FIG. 3, a sprinkler head nozzle 17 is retained by the hose receiver 70 of the exemplary portable hose stand system 10 to produce a water spray 11 that is directed upward to act as a sprinkler for a lawn, for example.

As shown in FIG. 4, the exemplary portable hose stand system 10 has a hose motion sensor valve 190 comprising a motion sensor 90 that is coupled with a valve 95 that opens and closes as a function of motion being detected. The motion sensor may produce a sensor curtain 92 of light produced by a light emitter 91, and received by a receiver 93. The light emitter may include a light emitting diode. Breaking the light curtain by inserting a hand between the emitter and receiver is detected by the motion sensor and activates the valve actuator 98 to open or close the valve 95. The motion sensor valve has a water conduit 195 with an inlet 94 and outlet 96. The motion sensor valve may be battery operated and have one or more batteries 99. A lock-out switch 97 is configured to deactivate the motion sensor to enable uninterrupted use when operating the portable hose stand or to close the valve and lock it when not in use. Switching the lock-out switch will disable the valve actuator. Note that the light produced by the light curtain may be a visible or non-visible light.

As shown in FIG. 5, the exemplary portable hose stand system 10 is secured on a ground surface 150 by the extension leg 41, extending from the stand body 30 and two retractable legs 40, 40' that are pivoted away from the extension leg by a leg assembly pivot 60 and away from each other by a leg pivot 36. The leg receptacle 32 may automatically pivot away from the extension leg and the two retractable legs may automatically pivot away from each other when the leg release 34 is actuated. As shown the retractable leg and the leg receptacle are pivoted away from the extension leg 41 a retractable leg angle 67 and the two retractable legs 40, 40' are pivoted away from each other a leg angle 37. Again, the leg assembly spring 62 and the leg pivot spring 38 may be released when the leg release 34 is actuated. The retractable legs may be individually extended to a desired length by pulling the first leg extension 44 out from the leg body portion 42 and securing in position by the first leg retainer. The stand assembly 33 may be placed on uneven ground and this individual adjustment and retention of the retractable leg length may provide better stability of the stand.

As shown in FIG. 6, the exemplary portable hose stand system 10 is secured on a ground surface 150 and has a weight 120 coupled to the stand body 30 to prevent the stand assembly 33 from tipping over during use. The weight is a bucket 122, such as a collapsible bucket 124 having a weight retainer 126, such as a handle or loop to enable the weight

bucket to hang from the stand assembly. In an exemplary embodiment, the weight 120 is a collapsible bucket 124 that can be filled with water to provide effective weight to stabilize the stand assembly 33. The collapsible bucket may be made from a fabric, which may be a coated fabric to make it waterproof. As shown in FIG. 6, the retractable legs 40, 40' each have a leg body portion 42, 42' and a first leg extension 44, 44' retained by the first leg retainer 45, 45'. Each of the legs has a ground end 49, 49' 49" that may be detachably attachable to the leg.

Referring now to FIGS. 7 to 10, the exemplary portable hose stand system 10 is collapsible or retractable wherein the retractable legs 40, 40' are pivoted toward each other and toward the extension leg 41, and with the first hose extension 56 and coupled hose extension 51 retracted down to the stand body 30. The first hose extension may be slid down into the coupled hose extension and the coupled hose extension may be slid down into the extension leg. Also, as shown, the nozzle pivot 80 enables the hose retainer 70 to pivot for a desired water spray orientation. The hose retainer 70 has a receiver clamp to allow insertion of a hose therein. As shown the hose extension retainer 53 is configured to secure the coupled hose extension 51 in a position with respect to the stand body 30 and extension leg 41.

Referring now to FIGS. 11 to 14, the stand assembly 33 includes the stand body that couples together the legs and the hose extension. The stand body includes the top of the extension leg, the hose extension retainer 53, the leg receptacle 32 for the two retractable legs, the leg assembly pivot 60 and the pivot retainer 68. The two retractable legs, 40, 40' are configured to pivot away from the extension leg 41 a retractable leg angle 67. The retractable legs are coupled with the leg receptacle 32 which pivots away from the extension leg by the leg assembly pivot 60 secured to the extension leg by the pivot retainer 68. A leg assembly spring 62 may force the retractable legs and the leg receptacle for the retractable legs away from the extension leg when the leg release 34 is actuated. As best shown in FIG. 12, the leg assembly pivot 60 may have a plurality of notches or pivot pin apertures 61 to receive a pivot pin 63 to retain the leg assembly in a pivoted position away from the extension leg 41. The two retractable legs pivot away from each other to a leg angle 37 by the leg pivot spring 38, which may be a torsional spring. Both of these two pivoting motions may be automatic upon actuating the leg release 34. The two springs, the leg assembly spring 62 and the leg pivot spring 38 may automatically force the retractable legs from the extension leg and spread the two retractable legs away from each other about the leg pivot 36.

Referring now to FIGS. 15 to 19, a hose motion sensor valve 190 has a motion sensor valve 95 coupled with valve actuator 98 to open and close a valve for water supply to from the inlet 94 to the outlet 96. The valve actuator 98 is coupled with the motion sensor 90 that detects when a sensor curtain 92, such as a light curtain 197, is interrupted, such as by placing a hand between the emitter 91 and the receiver 93. The motion sensor housing 191 forms a sensor pocket 193 for the sensor curtain 92 so that the valve is not inadvertently switched while manipulating the hose or hose nozzle (not shown). A first flange 192, which is an emitter flange comprising the emitter 91, and second flange 192', which is the receiver flange comprising the receiver 93, extend out to form the sensor pocket 193. The emitter flange and receiver flange have a length 105 that forms the sensor pocket having a depth 107 of at least 25 mm and preferably 35 mm or more, 50 mm or more, or even 70 mm or more and any range between and including the values provided.

The motion sensor valve has a water conduit 195 with an inlet 94 and outlet 96. The inlet 94 may have an inlet hose coupling 194 which may comprise threads 199 for coupling with an extended end of a hose. The outlet 96 may have an outlet coupling 196 that may also have threads 199' for coupling with a hose nozzle, or a sprinkler head.

A controller 198 may be configured to control the valve actuator 98 and may receive a signal from the motion sensor 90. One or more batteries 99 may provide electrical power for operations of the motion sensor valve and may supply electrical power to the controller, the light emitter, light receiver, motion sensor, lock-out switch and valve actuator. A lock-out switch 97 may enable a user to lock-out the valve 95 to maintain a water flow or prevent water flow through the motion sensor valve.

As shown in FIG. 20, the exemplary portable hose stand system 10 is detachably attached to a wall mount 25 by the wall mount clips 26, 26' that extend around the extension leg 41. The hose extension may be extended to enable the portable hose stand system to be used as a faucet or shower while mounted to the wall 24. Also, the nozzle pivot 80 is inserted into the first hose extension and is retained by a nozzle pivot post retainer 86, such as a ball, on the nozzle pivot post 84, shown in FIG. 26, extending into a nozzle-extension retainer 59, such as an aperture, for the ball to extend therethrough.

As shown in FIG. 20, the hose 12 extends from a water source end 14 coupled with a water source 15, such as a hose bib on a building, to an extended end 16 that is coupled with the hose receiver 70. The hose may be flexible such that it can be coiled into a coil having a diameter of 1 m or less.

Referring now to FIGS. 21 to 24, an exemplary wall mount 25 has a pair of wall mount clips 26 configured to receive the extension leg. This spaced apart arrangement of the wall mount clips provides better and more effective retention of the hose stand system assembly 10. Apertures are configured through the wall mount body 28 for securing the wall mount 25 to a wall.

Referring now to FIGS. 25 to 27, an exemplary hose receiver 70 has a receiver clamp 71 to open and close the hose receiver channel 72. The receiver clamp 71 is coupled with the first receiver portion 73 and the second receiver portion 75 about the hose receiver pivot 74. Squeezing the receiver clamp actuates the first receiver portion 73 to move away from the second receiver portion to open the receiver channel 72 for insertion of a hose. Also, the hose receiver is coupled with the nozzle pivot 80 that enables the hose receiver to be pivoted as desired and then locked into position by the nozzle pivot lock 82, such as a knob that can be turned. The nozzle pivot post 84 extends from the nozzle pivot 80 and has a nozzle pivot post retainer 86 to secure said post in a receiver.

As shown in FIG. 28, the hose receiver 70 shown in FIG. 25 is coupled with a wall mount 25 by the nozzle pivot post 84 being inserted into wall mount adaptor 22 having a wall mount retainer 27 to engage with the nozzle pivot post retainer to retain the nozzle pivot post therein. These retainers may be a ball and detent arrangement.

It will be apparent to those skilled in the art that various modifications, combinations and variations can be made in the present invention without departing from the scope of the invention. Specific embodiments, features and elements described herein may be modified, and/or combined in any suitable manner. Thus, it is intended that the present invention cover the modifications, combinations and variations of this invention provided they come within the scope of the appended claims and their equivalents.

What is claimed is:

1. A portable hose motion sensor valve system comprising:

- a) a hose
  - extending from a source end coupled to a hose bib, to an extended end;
  - wherein the hose is flexible and configured to be coiled into a coil;
- b) a water source having said hose bib;
- wherein the source end is detachably attached to the hose bib;
- c) a motion sensor valve comprising:

- i) a housing;
- ii) an inlet hose coupling configured on said housing and detachably attached with the hose to receive a flow of water from said water source said inlet hose coupling comprising threads;
- iii) an outlet coupling configured on said housing and comprising threads;
- iv) an emitter flange that extends a flange length from said housing;
- v) a receiver flange;
- vi) a sensor pocket formed in the housing between said emitter flange and said receiver flange;
- vii) a light emitter configured in the emitter flange;
- viii) a light receiver configured in the receiver flange;
- ix) a light curtain configured between the light emitter and the light receiver;

wherein the light curtain extends across the sensor pocket;

- x) a conduit extending within the housing and having an inlet coupled with the inlet hose coupling and an outlet coupled with the outlet coupling;
- xi) a valve coupled with said conduit; and
- xii) a valve actuator coupled with the valve and configured to open and close the valve; and

d) a nozzle comprising threads wherein the nozzle is threadably coupled to the threads of the outlet coupling; wherein the valve and valve actuator are configured between the inlet hose coupling and the outlet coupling of the motion sensor valve; and

wherein the valve actuator is configured to open the valve when the light receiver senses that the light sensor curtain is interrupted;

wherein motion sensor valve is configured between the extended end of the hose and the nozzle and wherein the motion sensor valve is portable and configured to move with said extended end of said hose; and

wherein each of the valve, valve actuator and light emitter, light emitter flange light receiver and light receiver flange configured on or in the housing of the motion sensor valve.

2. The portable hose motion sensor valve system of claim 1, wherein the motion sensor valve further comprises a controller that receives a sensor signal from the light receiver and that controls the opening and closing of the valve.

3. The portable hose motion sensor valve system of claim 1, wherein a controller receives a sensor signal from the light receiver.

4. The portable hose motion sensor valve system of claim 1, wherein the light emitter is a light emitting diode.

5. The portable hose motion sensor valve system of claim 1, wherein the light emitter emits a non-visible light.

6. The portable hose motion sensor valve system of claim 1, further comprising a lock-out switch to prevent the controller from switching a position of the valve from open

to closed or from closed to open, wherein the position of the valve is fixed when the on/off switch is in an off position.

7. The portable hose motion sensor valve system of claim 1, further comprising a battery that provides electrical power to hose motion sensor valve. 5

8. The portable hose motion sensor valve system of claim 1, wherein the emitter flange has a depth of at least 25 mm.

9. The portable hose motion sensor valve system of claim 1, wherein the emitter flange and the receiver flange each have a length of at least 25 mm to form the sensor pocket 10 having a depth of at least 25 mm.
